BALL INITIALING MACHINE

Cloyd D. Smith, Pacific Palisades, Calif., assignor
to Ball Renu, Inc., Los Angeles, Calif.

Application August 30, 1949, Serial No. 113,200

6 Claims. (Cl. 101—42)

1

This invention relates to imprinting machines, and has as its general object to provide an improved, simplified machine for imprinting objects particularly of a spherical shape. The invention is particularly useful for the purpose of imprinting initials upon golf balls.

One of the objects of the invention is to provide a fully automatic, coin controlled ball imprinting machine. Another object is to provide a ball imprinting machine having means for selecting and setting the indicia to be imprinted upon a ball or the like. Another object is to provide such a machine capable of imprinting by a process of transferring a pigment coating from a carrier ribbon onto the article to be imprinted.

Another object is to provide a ball imprinting machine that is of relatively simple and inexpensive construction.

Fig. 1 is a rear view, with the door open, of a machine embodying my invention;

Fig. 2 is a horizontal sectional view thereof taken on the line 2—2 of Fig. 1;

Fig. 3 is a vertical sectional view thereof taken on the line 3—3 of Fig. 1;

Fig. 4 is a detail view of a portion of the front of the machine showing the setting mechanism;

Fig. 5 is a schematic view of the electrical operating circuit of the machine;

Fig. 6 is a detail sectional view of a printing unit;

Fig. 7 is a front view of a modified form of the invention;

Fig. 8 is a rear view of the upper portion thereof, with the door open to expose the mechanism; and

Fig. 9 is a vertical sectional view through the front panel of the same.

As an example of one form in which the invention may be embodied, I have shown in the drawings a golf ball imprinting machine in which a golf ball 10 may be inserted into the machine and moved to a position from which it may be picked up by a work feed unit 11 and elevated into engagement with imprinting means 12. Interposed between the work feed unit 11 and the imprinting means 12 is a printing ribbon 13 through which impressions of type on the imprinting unit 12 are transferred onto the ball 10 when the latter is pressed upwardly against the type. The feed unit 11 is raised, and the ribbon 13 is advanced, by common operating mechanism which is indicated generally at 14. The operation is controlled by the coin-operated control unit indicated at 15.

The machine has a casing including a front wall 16, top and bottom walls 17 and 18, end walls 19 and a door 20 hinged to one of the end walls 19 as at 21. The operating mechanism is mounted upon a bracket including a base 22 and a vertical plate 23, the latter attached to the rear face of front wall 16. Front wall 16 and bracket plate 23 have a ball receiving opening 24 which is flanked by a pair of slideways 25 projecting rearwardly therefrom into the casing.

2

Slideways 25 may be mounted in any suitable manner as by means of a bracket 26 secured to the rear face of plate 23. Mounted in slideways 25 is a ball transfer slide 27 which has a circular opening 28 forming a seat for the ball 10. At the rear side of opening 28 is an upwardly extending stop 29 which functions to prevent accidental loss of a ball within the machine from improper manipulation of slide 27. Slide 27 has a handle 30 by means of which it may be moved inwardly and outwardly with reference to the machine. Slide 27 extends through opening 24 as shown in Fig. 3.

In the outermost position of slide 27, which may be determined by engagement of stop 29 against the plate 23, opening 28 is located outside the machine so that a ball 10 may be easily placed on the slide in a position seated in the opening 28. In the innermost position of the slide, shown in Fig. 3 (which may be determined by engagement of handle 30 against the front of the machine) ball 10 is centered above the feed unit 11 in a position to be picked up thereby and raised into engagement with imprinting units 12.

Feed unit 11 comprises a head 31 having an upwardly facing concave seat to receive the bottom of ball 10, and a shaft 32 on which head 31 is mounted. The lower end of shaft 32 is slidably received in a bore in a cam follower 33. The upper portion of shaft 32 is slidably mounted in a bearing 90 attached to plate 23 and follower 33 is slidably mounted in a bearing 91 attached to plate 23 and in turn provides a bearing for the lower end of shaft 32.

The lower end of follower 33 is bifurcated to embrace the upper extremity of an operating cam 34. In the bifurcated portion of follower 33 is journalled a roller 35 which rides upon the periphery of cam 34. Upward movement is transmitted from cam 34 through follower 33 and through a compression spring 36 to shaft 32. Compression spring 36 rests upon a flange 37 on the upper end of follower 33, flange 37 in turn resting upon bearing 91 in the lower limit of movement of follower 33. The upper end of spring 36 engages a nut 38 that is threaded upon an intermediate threaded portion of shaft 32 and is thereby adjustable to vary the compression load transmitted through spring 36. Thus the pressure with which the ball 10 is pressed against the imprinting unit 12, may be adjusted to the desired degree. A return spring 39 engaged between the nut 38 and a socket in bearing 90, effects the downward movement of the feed unit when such movement is permitted by cam 34.

The inner end of slide 27 is provided with an opening 101 to receive the head 31 in the event any mis-operation of the machine should result in the elevation of the unit 11 when the slide 27 is in its outer position.

The imprinting units 12, of which there are three, each include a mounting sector 102 having a semi-circular periphery to which is attached a

semi-circular type bar 103 carrying printing type 104. Each of the three type bars has type 104 corresponding to all letters of the alphabet. The periphery of each sector 102 has a channel 40 (Figs. 3 and 6) through which extends an electric heating element 41 for heating the type. Each sector 102 has a central hub which is rotatably mounted upon a shaft 42. Shaft 42 is mounted upon the plate 23 as shown in Fig. 3.

Each of the imprinting units includes a substantially semi-circular segmental internal gear 43, the ends of which are mounted in the corners of respective mounting sectors 102. Meshing with the internal teeth of the respective gears 43 are pinions 44. Pinions 44 are mounted on three shafts 45 each suitably supported for rotation as by means of bearing 46 mounted on plate 23. Shafts 45 extend through the front wall 16 of the casing and are provided with operating knobs 47. The gears 43 are of progressively greater diameter from front to rear so that the middle and rear gears have peripheral portions projecting beyond the periphery of the forward gear. The peripheral portions of the respective gears constitute dial faces bearing indicia 48 visible at the periphery of the forward gear and the projecting peripheries of the intermediate and rear gear respectively as indicated in Fig. 4. The indicia 48 each comprise the letters of the alphabet, and are so positioned that when a given letter 48 is visible through vertical slot window 49 in the front casing wall 16, the corresponding type element 102 will be in printing position centered above the elevating unit 11 so as to properly imprint the selected letter upon a ball 10.

A light bulb 50 (Fig. 1) may be embodied in the top of the casing to illuminate the dial faces of gears 43.

The operating mechanism 14 includes an electric motor 51 mounted upon base 22 and having a reduction gearing unit 52 including a driven shaft 53 which projects forwardly and has secured to its forward end the cam 34. The cam 34 has two dwell portions 54 and two lobes 55, whereby in each rotation of the cam through 180°, the feed unit 11 will be elevated from the starting position shown in Fig. 1 in which its roller 35 is associated with a dwell 54, through the elevated imprinting position in which the ball is pressed against type 104, this position being determined by the riding of roller 35 at the apex of a lobe 55, and back to the starting position of feed unit 11, determined by the movement of the other dwell 54 to a position centered beneath roller 35. Rotation of cam 34 as viewed from the rear in Fig. 1, is counterclockwise as indicated by the arrow.

Ribbon 13 is wound upon two reels 56, 56' the latter being connected to a ratchet wheel 57. Ribbon 13 extends from reel 56' over rollers 58 which guide it between ball 10 and imprinting units 12, and thence is rolled onto reel 56. Reel 56 is driven by a pawl 105 the lower end of which is pivoted to the horizontal arm of a bell crank 59. A depending arm of bell crank 59 rides upon the periphery of cam 34 at a point substantially 90 degrees from roller 35. Accordingly, when unit 11 is being raised, pawl 105 will retract under the pull of a spring 106 and as unit 11 is being retracted downwardly, pawl 105 will be moved upwardly to advance reel 56 one notch, thereby advancing ribbon 13 to a new position between feed unit 11 and imprinting unit 39. The retracted position of pawl 105 may be ad-

justed by an adjustable abutment screw 60 threaded through a bracket 61 projecting from plate 23.

The control unit 15 may be of any conventional coin operated type including a suitable good coin selector and slug rejector indicated in Fig. 1 at 62, a coin slot 63 through which the coin must pass in going through the unit 15 (or leaving it) and a micro-switch 64 having an arm 65. The end of arm 65 operates in an arcuate slot 66 in chute 63, is engaged by coin 67 as the latter passes through chute 63, and is thereby moved downwardly, closing switch 64. Coins leaving the unit 15 may drop into a coin collecting receptacle 68.

Referring now to Fig. 5, the coin operated switch 64 functions to initially energize a relay R through a circuit including a conductor 70, energizing coil 71 of relay R, and conductors 72 and 73 leading from a source of electric power such as the 110 volt source indicated. Once energized, relay R remains energized through one cycle of operation of the machine. This is accomplished by a holding coil circuit including a holding coil 74 in relay R, a conductor 75, a normally closed limit switch 76, a conductor 77, a normally open switch 78, a conductor 79 leading to one side of power circuit 72, 73, and a holding coil switch 80 in relay R, connected to the other side of the power circuit as shown. Normally open switch 78 is closed by engagement of inner end of slide 27 with its movable switch arm when slide 27 has been pushed into its inner position shown in Fig. 3.

The closing of relay R operates to establish a circuit through motor 51, through a main switch 81 of relay R, and conductors 82, 83 leading to the power circuit.

Switch 76 is a limit switch for terminating a given cycle of operation, and includes a movable switch arm which is engaged by one of two pins 84 carried by cam 34. The parts are arranged so that after being deenergized, motor 51, which does not include quick braking mechanism, will coast sufficiently to clear the end of the movable arm of switch 76 of contact with a pin 84 that has just engaged it, thereby allowing the switch 76 to return to its normally closed position.

Heating elements 41 are energized through a circuit including a transformer 85 the primary of which is connected to power circuit 72, 73 and the secondary of which is connected through a rheostat 86 and conductors 87, 88 to the elements 41, in parallel. A master switch 89 is incorporated in the power supply line 72, 73, to connect the machine to and disconnect it from the power supply. The circuit to the heating coils is connected directly across switch 89 so as to be energized whenever the switch 89 is closed.

As shown in Figs. 7 and 8, the imprinting unit, instead of being of arcuate form, arranged for pivotal adjusting movement, may be in the form of straight slides arranged for horizontal sliding movement. Fig. 8 illustrates a slideway 93 in which three slides 94 are arranged side by side. Each slide 94 carries type 39. Attached to the respective slides 94 are arms 95, 95', 95'' which project upwardly just behind the plate 23a, the latter being provided with horizontal slots 96. Stems 97, attached to the upper ends of arms 95, project forwardly through slots 96, and, in the front of the machine, are provided with pointer knobs 98 for manipulating the three slides. Pointer knobs 98 cooperate with three rows of letters 99 imprinted on the front panel 16a of the machine. The panel 16a is indented and is

illuminated by a light 50a mounted inside the machine and shining through a window 49a. The remainder of the machine is the same as in the preferred form of the invention described above. Each machine may carry on its front wall an instruction plate 100.

Operation

The instructions on the plate 100 (which is on the machine of either modification) directs the user to first place a ball 10 in slide 27 and to then push the slide inwardly to the limit of its possible inward movement. This brings the ball 10 to the operative position shown in Fig. 3 and closes the switch 78 of the holding circuit. The operator is directed to then place a coin in the coin slot (not shown). In passing through the control unit 15 the coin will trip switch 64, momentarily energizing main coil 71 of relay R and closing both switches 80 and 81. The closing of switch 80 establishes a holding circuit, switch 76 being normally closed and switch 78 having been closed by slide 27. The energizing of the holding coil functions to hold the relay R closed until the holding coil circuit is opened by the opening of switch 76.

With the relay R closed, motor 51 will operate to rotate cam 54, raising feed unit 11 into engagement with ball 10, picking up ball 10 and moving it upwardly into engagement with the three selected type elements 104, with ribbon 13 interposed between the ball and the type. The pressure of the ball against the type is that of the loading of spring 36. Impressions of the heated type 104 are transferred to the ball 10 through ribbon 13, corresponding sections of ribbon 13 being pressed into the surface of ball 10. The continued rotation of cam 34 allows feed unit 11 to be returned downwardly under the pressure of spring 39. At the same time, pawl 105 will be moved upwardly, acting against the ratchet wheel 57 to rotate reel 56 and advance ribbon 13 to a position for the next operation. As the cam 34 approaches the position shown in Fig. 1, one of its pins 84 will engage switch arm of limit switch 76, opening the holding circuit of relay R, deenergizing the relay, and thereby opening the motor energizing circuit to terminate the cycle of operation. Motor 51 will coast sufficiently to carry pin past arm of switch 76, releasing it so that switch 76 closes, resetting the holding circuit for another cycle of operation.

I claim:

1. In a ball imprinting machine: a housing having an aperture for passage of a ball therethrough; a feed unit within said housing, including a ball support and means for moving said support on a vertical axis; imprinting mechanism within said housing, disposed above said support in a position to effect imprinting of a ball carried upwardly thereto by said support; a slide having an opening of larger diameter than said ball support whereby the support may pass therethrough, and having a ball seat for supporting a ball in a position centered over said opening; horizontal slideways in which said slide is mounted for movement transverse to said vertical axis, from a position in which a ball may be placed on said seat from the exterior of the housing to a position in which the ball is centered on said vertical axis above said ball support; said feed unit including means for moving said support vertically from a position disposed below the plane of said slide to a position

projected upwardly through said opening and presenting the ball to said imprinting mechanism.

2. A ball imprinting machine as defined in claim 1, wherein said imprinting mechanism comprises a plurality of shiftable type-bearing units, means for shifting said units individually to selected positions, a printing ribbon, and means mounting said ribbon with a portion of the same disposed between said support and said imprinting units, and for advancing said ribbon upon each successive actuation of the machine.

3. A ball imprinting machine as defined in claim 2, including a coin operated control device; and means controlled thereby for automatically effecting, in separated stages of operation, the actuation of said feed unit and the advancement of said ribbon.

4. A ball imprinting machine as defined in claim 1, including a coin operated control device; and means controlled thereby for automatically effecting the actuation of said feed unit.

5. A ball imprinting machine as defined in claim 1, including a coin operated control device; said last mentioned means including an electric motor and a circuit for energizing the same, said circuit including said coin operated control device and a second control device in series therewith and made operative by the movement of said slide to the position in which the ball is centered on said vertical axis, to set the circuit for energization by the actuation of said coin operated control device.

6. In a ball imprinting machine: a housing having an aperture for passage of a ball therethrough; a feed unit within said housing, including a ball support and means for moving said support on a vertical axis; imprinting mechanism within said housing, disposed above said support in a position to effect imprinting of a ball carried upwardly thereto by said support; a slide having an opening of larger diameter than said ball support whereby the support may pass therethrough, and having a ball seat for supporting a ball in a position centered over said opening; horizontal slideways in which said slide is mounted for movement transverse to said vertical axis, for carrying the ball into and out of the machine through said aperture, between a position in which said ball seat is disposed exteriorly of the machine, permitting the ball to be placed thereon or removed therefrom, and a position in which said opening is centered on said vertical axis so that said support may pass therethrough, engage the ball, and elevate it so as to present it to said imprinting mechanism, said feed unit including mechanism for moving said support on said vertical axis.
